HYDRAULIC TRANSMISSION

Dimitri Sensaud de Lavaud, Paris, France

Application July 3, 1934, Serial No. 733,696
In France July 8, 1933

8 Claims. (Cl. 60—54)

In certain previous Patents 2,034,429 and 2,080,199 I have described certain hydraulic transmissions designed especially for motor-driven vehicles, comprising a pump, a turbine and at least one vane stator between the turbine and the pump, and have described various details of control and adjustment. The apparatus is designed to operate as a hydraulic coupling between the pump and the turbine when the couple of the load is equal to that of the driving force. But it is practically impossible, without special provisions, to avoid a certain slip between the pump and the turbine.

In Patent 2,034,429 I have described means for partly remedying this disadvantage by freeing the vane stator automatically or at will when the resisting couple imposed by the load on the turbine becomes equal to the couple imposed by the motor on the pump, so that the vane stator could be carried along in the same direction and at substantially the same speed as the turbine and the pump. But with this device there has still been a certain slip (of the order of 3 to 4 per cent) between the turbine and the pump because the vane stator retards the passage of the oil or other fluid.

The present invention aims to remove this defect by connecting the turbine and the pump automatically at a determined speed of rotation of the pump. When the motor is started, the load is comparatively great and the pump drives the turbine at a reduced speed. As the resistance diminishes the speed of the turbine increases and also that of the pump, the relative speed of the turbine gradually approaching that of the pump. The connecting means are set to operate at the speed of the pump which is attained when the resisting couple has diminished to approximate equality with the driving couple.

This rigid connection between the pump and turbine is also set for that driving couple or force at which the motor operates with maximum efficiency, that is to say, for a determined speed of the motor and, consequently, of the pump.

The fixed connection may be effected automatically by any suitable means by various suitable devices, mechanical or otherwise; the connecting devices in turn being controlled either by the speed of the turbine or (preferably) by the speed of the pump or by both.

Preferably also the turbine shaft actuates a driven shaft by an intermediate gearing, which may be of the planetary type and which is adjustable to different positions for actuating the driven shaft forward at the same speed as the

driving shaft, forward at a reduced speed or backward, at will.

The invention includes also a certain number of particular features described in detail hereinafter. The accompanying drawings illustrate one example.

Fig. 1 is a longitudinal central section of the complete apparatus, partly in elevation. Fig. 2 is an elevation, partly in section, of the devices for connecting the pump and the turbine. Fig. 10 3 is a transverse section, the parts in different planes, through certain controls of the planetary transmission. Fig. 4 is a similar section of means for rigidly connecting the turbine shaft with the driven shaft. Fig. 5 is a section approximately 15 on the line V—V of Figs. 3 and 4. Fig. 6 is an end view of the shaft and lever shown in Fig. 5. Fig. 7 is a transverse section of a pawl and ratchet between the vane stator and the frame of the apparatus. Fig. 8 is a detail in section 20 on a larger scale of the mechanism for braking one of the sets of planetary pinions.

Fig. 9 is a front view of the said wedges, the shell of the turbine being removed or omitted and two of the wedges being shown partly in section for showing the engaging method of the springs which connect the said wedges together.

Fig. 10 is a section on line X—X of Fig. 9.

Fig. 11 is a section on line XI—XI of Fig. 9.

Fig. 12 is a section on line XII—XII of Fig. 9. 30

The hydraulic transmission mechanism illustrated by way of example comprises a pump 1 fixedly mounted on a shaft 2 driven by the motor, a turbine 3 co-axial with the pump and a ring 4 carrying blades and serving as a vane 35 stator when a centrifugal pump is used or only as a directing ring when a helicoidal pump and turbine are used. The ring 4, turbine 3 and pump 1 provide a practically closed circuit for the fluid within the mechanism.

The vane stator ring 4 is carried on a disc 4^a which is mounted on a ball bearing carried by the hub of the turbine. Balanced pawls 82 (Figs. 1 and 7) are pivoted on pins 83 fixed on the disc 4^a. The free ends of the pawls are spring-pressed inward against a ratchet 84 carried by a hub 85 which is connected to sleeves 86. The sleeves are fixed at their other ends to the frame 36. Thus the vane stator is free to rotate with the turbine and the pump but is fixed against 45 backward rotation.

The oil or other fluid within the casing is maintained under pressure by means of a gear pump, of which one pinion 87 is fixed on a sleeve 88 attached to the shell of the pump 1. The other 50

pinion 89 is mounted loosely on an axle 90 fixed on a casing 91 which encloses this pump and is fastened to the frame 36.

The losses of the fluid are recovered in a channel 92 whence they return through a conduit 93 to the feed reservoir.

The means for connecting together the pump and the turbine, of the type described or of various other types, is illustrated particularly in Figs. 1 and 2. On the portion 1^a of the shell of the pump there is mounted a plate 1^b having its outer portion offset and carrying three guide blocks 1^c which enter grooves in three blocks 80 spaced at equal distances from each other and drawn inward by means of connecting springs 81 of determined tension. When the speed of rotation of the pump produces a centrifugal force sufficient to offset the resistance of the springs, the blocks 80 are pressed against the shell of the turbine 3 and constitute a connection sufficiently rigid to prevent slip between the pump and turbine.

When the speed of the pump falls to the determined extent, the springs withdraw the blocks. The inward movement of the blocks is facilitated by inclining their grooves and the guide blocks 1^c forward, that is in the direction of rotation as shown by the arrow, Fig. 2. The angle *a* between the radial direction and the direction of the movement of the blocks is made equal to the angle of friction.

The connection between the pump and the turbine takes place at a determined rate of rotation of the pump. Preferably this rate is that at which the couple of the force exerted by the motor upon the pump is equal to the couple of the resistance or load on the turbine. This corresponds to the instant when, after starting at a reduced speed there is a gradual lessening of the resistance and finally the speed reduction of the hydraulic mechanism ceases. Preferably also the chosen speed at which the connection is effected is that at which the motor has a maximum efficiency.

Automotive engines are designed to work with maximum efficiency at a certain speed or range of speeds of rotation of their crank shaft. By effecting a rigid connection between the pump and the turbine at this speed, the motor will be operated at its highest efficiency over the principal part of the time that it is in use.

The principle of the invention may be applied to other types of hydraulic transmission and for other speeds and may utilize other types of connector than as illustrated. The connecting devices may be controlled mechanically and either by the speed of the pump or that of the turbine or by the relation between these two speeds or the relation between the driving and the resisting forces acting on the pump and the turbine respectively.

The hydraulic transmission is preferably combined with mechanism between the turbine shaft and a driven shaft by which the latter can be rotated forward at the same speed as the turbine shaft or forward at a slower speed or backward. A planetary gearing is illustrated for this purpose in Fig. 1, with details in Figs. 3, 4, 5, 6, and 8.

The hub of the turbine 3 is keyed on the left end of a turbine shaft 5. Fixed to the other end of this shaft is the head 7 of a drum 6, 7, 7^a. Within the drum are three groups of pinions 8, 9, and 10 mounted freely on shafts 11

which are fixed in the heads 7 and 7^a of the drum.

It will be understood that there are several groups of such pinions spaced angularly around the drum, as usual in planetary gearing. The diameter of the pinions is chosen in order to give the correct speed reduction forward and backward.

Where more than one speed reduction is desired, a larger number of pinions may be used in each group.

The pinion 8 engages a pinion 12 fixed on the left end of a driven shaft 13 which carries at its other end a coupling device 14. The pinion 9 engages a pinion 15 fixed on a sleeve 16 which is concentric with the driven shaft 13 and on which is splined the hub 18 of a disc 17, so that the disc can slide longitudinally on the sleeve 16. A pinion 12^a carried by a sleeve 24 is engaged by the pinion 10.

The disc 17 has two annular tapering grooves in each face near its periphery. Any number of such grooves may be provided. The drum head 7^a has corresponding annular ribs 21 facing the grooves at one side. At the opposite side is a disc 23 provided with corresponding ribs 22. The hub of the disc 23 is angularly fixed on the sleeve 24 but is movable axially thereon.

Means are provided as follows for clamping the disc 23 against rotation, or for freeing it. On its periphery it has teeth 25 which have an axial sliding engagement with corresponding internal teeth in a ring 26 which may be clamped or released as hereinafter described.

The disc 17 has a peripheral flange 27 which is also provided with external teeth 28 having an axially sliding engagement with internal teeth carried by a ring 29 which may be clamped fast or released. The disc 23 is pressed outward by springs 30 positioned between the discs 23 and 17. Similarly the disc 17 is pressed outward by springs 31 bearing against the head 7^a of the drum. When these springs are effective the ribs are withdrawn from the grooves sufficiently to permit free rotation between the drum, the disc 17 and the disc 23.

The parts are pressed together and the ribs forced into the grooves of the disc 17 by devices which force the disc 23 inward. On the hub 52 of the disc 23 is fixed the internal race of a ball bearing, of which the external race is carried by a ring 32. The ring 32 can be forced to the left against the pressure of the springs, thus forcing the ribs into the groove and by their friction connect the drum head 7^a and the discs 17 and 23 firmly together. This effects a fixed connection between the turbine shaft 5 and the driven shaft 13.

The axial shifting of the ring 32 is effected by giving it a slight angular displacement. See Figs. 1 and 4. The ring has ears 33 connected by rocking pins 34 normally inclined obliquely between the ring 33 and a plate 35 fixed to the frame 36 of the apparatus. In the inclined position of the rockers the ring 32 is retracted to the right. A slight turn of the ring 32 shifts the rockers toward the right angled position and pushes the ring 32 outward.

The angular movement of the ring 32 is produced by a cam 39 bearing on a roller 37 carried by a plate 38 fixed to the ring 32. The roller is held adjacent the cam by means of a spring 40 engaging a pin on the plate 38 and connected at its opposite end to a cap 41 by means of a threaded rod 42 and nuts 43 for regulating the 75

tension; the cap being mounted on a part of the casing surrounding the ring 32.

The cam 39 is keyed on a shaft 44 (Fig. 5) mounted in bearings 45 and 46 carried by the frame. This shaft carries at its outer end a ratchet 47 having a number of teeth corresponding to the number of high and low points of the cam, so that a rotation for a distance of one tooth turns the cam from a high point to a low point, or vice versa, and effects a corresponding maximum movement of the ring 32. The operation of the shaft 44 is effected by a lever 48 mounted thereon and carrying a pawl 49 (Fig. 6) held in engagement with the ratchet by a spring 50. Thus alternate oscillations of the lever 48, by means of a pedal or the like, operate the shaft 44 through a determined distance, the movement in the direction of the arrow alone operating the shaft.

Each movement of the lever 48 therefore locks the disc 17 with the drum 6 and the disc 23, or releases these three parts from one another.

The rings 26 and 29 are preferably made of bronze or the like. They are fixed against angular movement with respect to the discs 17 and 23. When these rings are clamped against movement the corresponding discs are also held fast. The outer faces of the toothed rings bear against annular ribs 53 and 54 fixed to the frame, integrally or by attachment thereto.

On the inner sides of the toothed rings are brake rings 55 and 57 adapted to slide axially and a fixed ring 56 in the center. The central ring serves as an abutment for devices which press the brake ring 55 outward to clamp the toothed ring 29 and thus hold the disc 17 stationary, or to press the brake ring 57 outward against the toothed ring 26 and thus hold the disc 23 stationary.

The center ring 56 is fixed in the casing by means of a screw 56^a, Fig. 3, and is lodged in a groove 69, Fig. 1, in the casing which prevents axial movement. The brake rings 55 and 57 can be turned and also shifted laterally. The central ring carries on each lateral face inclined recesses 58 approximately opposite the similar recesses 59 in the brake ring (Fig. 8). Between the two recesses is a ball 60 which when the brake ring is turned in one direction rides on the inclines and forces the brake ring firmly against the toothed ring in question; and which, when the brake ring is moved in the opposite direction, lies in the deeper parts of the grooves and removes the clamping action.

The rotation of the clamping rings is obtained by means of cams 61 and 62 (Figs. 3 and 5). They are splined on the shaft 44 and are set at a right angle to each other. Fig. 3 is in two planes of section illustrating the two clamping rings 55 and 57. Each of these has a projection 64 lying between a rod 63 forced in one direction by the cam and a rod 65 forced in the opposite direction by a spring 66 held by a cap 67. The springs turn the rings to the clamping position. The cams turn them to the released position. Fig. 3 shows them both released (or they may both be clamped) at one time.

The two cams 61 and 62 are in one piece which is splined on the shaft 44 to permit axial displacement. The profile of the cams 61 and 62 corresponds to that of the cam 39 in having the same number of high points and low points oppositely placed.

The two cams 61 and 62 can be shifted to an inoperative position (leaving the clamping rings

in clamping position to hold the toothed rings stationary) by means of a finger 68 lying in a circumferential groove 69^a of the cam block and mounted on a crank 70 (Fig. 3) on a short shaft 71 to which is keyed a grooved pulley 72 whose rotation is effected by suitable means, such as a Bowden cable 73 for example. The positions of the pulley which correspond to the operative and inoperative positions of the cam block are determined by the engagement of a ball 74 carried by the pulley and pressed outward by a spring 75 and adapted to enter recesses formed in a part 77 which serves as a bearing for the shaft 71 and which is fastened to the frame 36 by a screw 78 or the like.

The cams 61 and 62 can take three positions; the first corresponding to a forward reduced speed, the second in which both cams are out of action and the discs 17 and 23 are firmly clamped to the drum and the third corresponding to the backward drive. The relative position of the cams 61 and 62 to that of the cam 39 is such that when the latter is at a low point (corresponding to a direct coupling of the turbine and the driven shaft) the two cams 61 and 62 are at their dead point.

The relation and function of various parts will now be explained in detail for a clearer understanding of the same.

On the shell 1 of the pump and on the surface 1^a of this shell situated opposite the shell 3 of the turbine, there are a certain number of blocks or wedges 80, namely three, in the constructional form shown in the various figures of the drawings. These wedges or blocks 80 are identical and relatively displaced at an angle of 120°. Each of these wedges 80 is designed circumferentially so as to have a thickness which decreases in such manner that the lateral faces of each of the said blocks form a wedge adapted to engage, when 40 these wedges are displaced outwardly, between the faces situated opposite and conformably to the shells of the pump 1 and of the turbine 3 for rigidifying these two shells as hereinafter explained.

The blocks 80 are arranged against the face 1^a of the shell of the pump and are held against this face by means of a cheek 1^d secured by any suitable means to the shell 1 of the pump. These blocks 80 are secured to the said cheek 1^d and 50 guided thereon through the medium of grooves 1^e formed in the said blocks and in which are adjusted projections or guides 1^c secured by any suitable means such as rivets 1^f to the cheek 1^d which is rigidly secured to the shell of the pump. 55

The blocks 80 are connected together by antagonistic springs 81 suitably calibrated so that the outward displacement of the blocks 80 under the influence of the centrifugal force created by the rotation of the shell of the pump on which are mounted the said blocks is effected for a definite speed of rotation of the said pump and which may be for example that speed for which the driving couple on the pump is equal to the resisting couple on the turbine.

According to the invention and for reasons which will be hereinafter explained, the grooves 1^e formed in the blocks 80 as well as the projections or guides 1^c rigid with the cheek 1^d are inclined in the corresponding radial direction and according to the direction of rotation at an angle equal in principle to the angle of friction α . The centrifugal displacement of the blocks 80 is thereby effected according to this direction inclined at the angle α to the corresponding radius extend- 75

ing in principle through the center of gravity of the block under consideration.

The operation of the rigidifying means is as follows:

- 5 It is assumed that the said wedges 80 are mounted on the shell of the pump as is the case in Figure 1 of the drawings. It is assumed that the pump 1 rotates at a speed higher than the speed for which the wedges or blocks 80 are displayed in antagonism to the springs 81 so as to rigidify the shells of the pump and turbine. There is then a rigid connection between the pump and the turbine without which there would be a slip between these two members, in other words there is a rigid drive between them. Assuming there exists a slight slip between the turbine and the pump, the turbine being the resisting member, this slip is only produced owing to the fact that the turbine tends to rotate less quickly than the pump. In other words, there exists a relative rotation between the pump and the turbine and this relative rotation takes place in the direction of rotation common to the pump and the turbine, that is to say, in the direction indicated by the arrow f in Fig. 9 of the accompanying drawings. It is obvious from this figure that this slip produces on the wedge 80 a series of forces whose resultant R applied to the center of the said wedge 80 is directed tangentially and in the direction of the arrow f . This force R is adapted to be separated into two forces, one force R_1 being directed according to the direction of displacement of the wedge 80 and the other R_2 directed perpendicularly to the said direction. The component R_1 tends to displace the wedge externally, that is to say, to penetrate this wedge between the rubbing surfaces of the pump and the turbine after the manner of a wedge in antagonism to the force of retraction F exerted by the springs 81 but in the same direction as the action of the centrifugal force which is greater than F . It is therefore obvious that a real wedging action is produced automatically and a slip between the pump and the turbine is prevented.
- 45 If the speed of the unit, formed by the pump and the turbine which are rigidified, decreases owing to the fact that the resistance on the driving wheels of the vehicle, on which the hydraulic transmission is mounted, increases, that is to say, the resistance on the turbine increases, it is obvious that in this case it is the turbine which reduces the speed of the unit or, in other words, the turbine tends to rotate less quickly than the pump. It is assumed that the speed of the unit (pump and turbine) decreases slightly below the predetermined speed or critical speed for which there is no rigid connection between the two members; an examination will now be made to ascertain what is produced on the return of the jamming wedges under the action of the springs.

An examination will be made of only one of the wedges and it will be assumed that the various forces under consideration are applied at a point A placed at the center of gravity of the said wedge. Owing to the rotation at a speed lower than the critical speed, it is obvious that the wedge is subjected to a centrifugal force of retraction F directed radially since at this moment, the action of the springs is greater than the action of the centrifugal force. On the other hand, if f indicates the direction of rotation of the unit (pump and turbine), it is obvious that the tendency of the turbine to rotate less quickly than the pump creates on the wedge, rigidly

connected to the pump, a force T directed in a direction of rotation f and due to the friction of the said wedge on the shell of the turbine, the said force T being tangent to the circle passing through the point A under consideration. On the other hand and on account of the friction between the wedge and the guide or the like provided on the shell of the pump—a friction which is opposed to the displacement—it is obvious that the actual force T' exerted on the wedge forms an angle α with the force T , the angle α being equal to the angle of friction. It is therefore obvious that the wedge is subjected to two forces F and F' : one force F is radial and the other force T' perpendicular to the direction of displacement of the wedge 80 under consideration since according to the invention, this direction is inclined at an angle α to the corresponding radius.

Consequently, there does not exist a component directed according to the direction of displacement and opposing the said displacement which can then be produced under the action of a very weak force, that is to say, with very weak antagonistic springs 81.

The functions of the several parts having been explained, a brief statement will serve to explain the operation of the whole.

When the pump 1 is driven by the motor, the fluid in the hydraulic circuit is displaced in the direction of the arrow 94 and drives the turbine. The speed of the turbine increases as the resistance diminishes. When it reaches a speed approximately equal to that of the pump, the vane stator is automatically freed and is carried along in the same direction as the turbine and pump. As hereinabove explained the blocks 80 are forced out by centrifugal force to connect the turbine and the pump and to prevent any slip between them. If the speed of the turbine diminishes, so does that of the pump rigidly connected to it, the connecting blocks are withdrawn by their springs, and the vane stator is stopped by the pawls engaging the ratchet.

To secure a direct drive of the shaft 13 by the turbine, the cams 61 and 62 are first put out of action through the pulley 72 and the crank pin 68. The drum and the discs 17 and 23 are connected by turning the cam 39 to the proper point by means of the arm 48.

To advance at reduced speed, the cams 61 and 62 are shifted on their shaft to bring them into operative positions. The lever 48 is then operated; (1) to release the drum and the discs 17 and 23 and (2) to turn the cams so as to clamp by cam 62 the disc 17 which engages and holds fast the pinion 15 corresponding to a backward movement.

For the backward drive at reduced speed the lever 48 is first actuated. Then the cams 61 and 62 are turned to the position corresponding to the backward movement and then the lever 48 is operated again.

The invention is not limited to the particular embodiments illustrated and described. Various modifications may be made in the several parts and in the arrangement thereof without departing from the invention as defined in the following claims.

What I claim is:

1. Improvements in hydraulic transmission mechanism comprising a driving shaft, a driven shaft, a rigid member including a pump keyed on said driving shaft, a rigid member including a turbine keyed on said driven shaft, a vane stator between the turbine and the pump, means actu-

ated by the centrifugal force at a certain speed of one of said shafts to rigidly connect said driving and driven shafts, said means wedging between rigid members on the driving and driven shafts respectively.

2. The device as claimed in claim 1, in which there are means for preventing the wedging means from acting in one direction of rotation.

3. Improvements in hydraulic transmission mechanism comprising a driving shaft, a driven shaft, a rigid member including a pump keyed on said driving shaft, a rigid member including a turbine keyed on said driven shaft, a vane stator between the turbine and the pump, means actuated by the centrifugal force at a certain speed of one of said shafts to rigidly connect said driving and driven shafts, said means wedging between the shell of the pump and the shell of the turbine.

20 4. Improvements in hydraulic transmission mechanism comprising a driving shaft, a driven shaft, a rigid member including a pump keyed on said driving shaft, a rigid member including a turbine keyed on said driven shaft, a vane stator between the turbine and the pump, means actuated by the centrifugal force at a certain speed of one of said shafts to rigidly connect said driving and driven shafts, said means wedging between rigid members on the driving and driven shafts respectively, and comprising wedging blocks carried by one of said members, yielding means suitably calibrated opposing the centrifugal force whereby the said blocks engage with the other member under the action of the centrifugal force created by a predetermined speed

of rotation of the member carrying the said blocks.

5. The device as claimed in claim 3, said wedging means comprising wedging blocks carried by the pump between the pump and the shell of the turbine, yielding means suitably calibrated opposing the centrifugal force whereby the said blocks engage with the shell of the turbine, under the action of the centrifugal force created by a predetermined speed of rotation of the pump. 10

6. Improvements in hydraulic transmission mechanism comprising a driving shaft, a driven shaft, a rigid member including a pump keyed on said driving shaft, a rigid member including a turbine keyed on said driven shaft, a vane stator between the turbine and the pump, means actuated by the centrifugal force at a certain speed of one of said shafts to rigidly connect said driving and driven shafts, said means wedging between rigid members on the driving and driven shafts, respectively, in which the wedging means comprise blocks and means for preventing their action in one direction of rotation and guiding means for causing the displacement of the block to take place at an angle to the corresponding radial direction, said angle being substantially equal to the angle of friction between the wedging blocks and the rigid members of the pump and the turbine. 15 20 25

7. The device as claimed in claim 4, in which said yielding means comprise springs connecting the block in pairs. 30

8. The device as claimed in claim 6, in which said yielding means comprise springs connecting the blocks in pairs. 35

DIMITRI SENSAUD DE LAVAUD.
